UNITED STATES PATENT OFFICE

171,101

SMOKER'S STAND OR SIMILAR ARTICLE

Fredric C. Panzer and Wilbur H. Panzer,
Chicago, Ill.

Application April 15, 1953, Serial No. 24,506

Term of patent 14 years

(Cl. D85—2)

To all whom it may concern:

Be it known that we, Fredric C. Panzer and Wilbur H. Panzer, citizens of the United States, both residing in Chicago, Cook County, Illinois, have invented a new, original, and ornamental Design for a Smoker's Stand or Similar Article, of which the following is a specification, a reference being had to the accompanying drawings, forming a part hereof.

We claim:

The ornamental design for a smoker's stand or similar article, substantially as shown.

FREDRIC C. PANZER.
WILBUR H. PANZER.
